FREDERICK KOHNLE, OF DAYTON, OHIO, ASSIGNOR TO THE MONARCH MARKING SYSTEM COMPANY, OF DAYTON, OHIO, A CORPORATION OF OHIO

PRICE TAG

Application filed February 20, 1929. Serial No. 341,443.

This invention relates to improvements in fasteners or clips particularly of the pin type for securing price marking tags or tickets to merchandise. The invention primarily is directed to a pin fastener having its ends looped about opposite edges of the tag and inwardly underneath the tag.

An object of the invention is to secure a tag or ticket to merchandise by a pin fastener in a manner in which the ends of the pin are concealed and guarded.

Another object of the invention is to secure a tag or ticket to merchandise by a pin fastener engaged through the tag and merchandise, with the ends of the pin looped or crimped relatively about opposite edges of the tag to extend inwardly toward each other underneath the tag.

Other features and advantages of the invention will be more fully set forth in the description of the accompanying drawings, in which:

Figure 1 is a plan view of a tag as applied with the improved fastener to a piece of fabric merchandise.

Figure 2 is a section on line 2—2, Figure 1.

Figure 3 is a sectional view of the tag and fabric in position to be secured together by the fastener, the fastener shown in elevation therewith in the form of a staple ready to be engaged through the goods and ticket.

Figure 4 is a similar view to Figure 1 of a modified form of fastener.

Figure 5 is a section on line 5—5, Figure 4.

Figure 6 is a view of the fastener shown in Figures 4 and 5, representative of a straight bar or shank having a hook end.

The form of fastener shown in Figures 1 to 3 inclusive, is characteristic of a staple, while the form shown in Figures 4 to 6 inclusive, is of a straight bar or shank with a preformed hook end. The designs of the pin or fastener and its method of application in securing the tag to the goods may be diversified and present a form most suitable to the class of merchandise to be ticketed.

For instance, the staple form is more ample for securing the tag to heavy fabric or binding several layers of fabric, while the pin form can be more advantageously uti-

lized for thin or light weight fabrics. In both instances, the ends of the fastener engage through the tag to present the same over the face sides toward its opposite edges, adapting the same to be looped over the edges in a return bend to extend inwardly upon the under face of the tag.

For the staple type, the wire is initially bent into U form, furnishing a cross bar 1 and a pair of parallel limbs 2—2, the limbs forced through the fabric or merchandise 3 and tag 4, preferably from the underside of the fabric, bringing the cross bar against the underside of the fabric and the limbs through to the upper side of the tag, from whence the ends are bent in opposite directions over the face side of the tag and about the opposite edges of the tag, and thence inwardly to lie underneath the tag, clinching the ends about the edges of the tag.

This brings the free ends of the wire between the tag and the fabric, completely housing and guarding the same, so that no sharp or barbed edges are exposed to prick the hands or into other pieces of fabric in stacking or packing the ticketed fabric merchandise.

The style of fastener shown in Figures 4 to 6 inclusive, representative as a pin, has a straight bar or shank 5 which is passed longitudinally into and through the tag and goods sidewise of the tag, and in its application the tag and merchandise are slightly bowed or curved for convenient insertion of the pin through the tag and merchandise from the face side of the tag, thence across the underside of the fabric, and again through the fabric and tag, bringing the opposite end of the pin on the face side.

One end of the pin preferably is preformed with a hook or bend 6 to engage about an edge of the tag and bring its free end inwardly underneath the tag, and the opposite end of the pin after it has engaged through the tag and goods is bent or crimped over the opposite edge of the tag and about the same, thence inwardly underneath the tag to correspond with the opposite preformed end, and similar to that described for the staple form.

Having described my invention, I claim:
Means for tagging merchandise, comprising,
a tag and a wire fastener for securing
the tag to the merchandise, the fastener con-
stituting a length of wire engaged through
the merchandise and tag at two points, the
opposite ends of the wire extending from the
upper side of the tag in opposite directions
over the side edges of the tag and clinched
thereto, with the free ends of the wire ex-
tending inwardly against the underside of
the tag.

In witness whereof, I hereunto subscribe
my name.
